UNITED STATES PATENT OFFICE.

WILLIAM T. SNELL, OF CALUMET, MICHIGAN.

CONDENSER FOR STEAM-ENGINES.

SPECIFICATION forming part of Letters Patent No. 588,497, dated August 17, 1897.

Application filed March 12, 1897. Serial No. 627,151. (No model.)

To all whom it may concern:

Be it known that I, WILLIAM T. SNELL, of Calumet, in the county of Houghton and State of Michigan, have invented a new and 5 Improved Condenser for Steam-Engines, of which the following is a full, clear, and exact description.

The object of the invention is to provide a new and improved condenser for steam-engines and arranged to prevent the water from accumulating in the casing of the condenser irrespective of the working of the pump and without causing back pressure on the engine.

The invention consists of a double valve 15 for directing the exhaust-steam either into the condenser-casing or to the atmosphere, the said double valve being controlled by a float in the condenser-casing.

The invention also consists of certain parts 20 and details and combinations of the same, as will be fully described hereinafter and then pointed out in the claims.

Reference is to be had to the accompanying drawing, forming a part of this specification, 25 in which the figure represents a sectional side elevation of the improvement.

The condenser is provided with a suitably-constructed closed casing A, from the bottom of which extends the suction-pipe B, connected with a pump or like device for drawing the water accumulating in the lower end of the casing A from the casing. On the upper end of the casing A is mounted a valve-casing C, connected with the exhaust-pipe D 30 of the engine, so that the exhaust-steam passes into the casing C and from the latter can either pass into the casing A or to the atmosphere, according to the position of a double valve arranged in the said casing.

The casing C is provided for this purpose with two valve-seats C' and C², of which the latter opens into the atmosphere and the other opens into the condenser-casing A. The valves C³ and C⁴ are adapted to be seated 40 on the said valve-seats C' and C², and the said two valves are attached to a common valve-stem C⁵, so that an up or down movement of the valve-stem causes the seating of one valve and the unseating of the other. A 45 spring C⁶, coiled on the stem C⁵, presses on the valve C³, so as to normally hold the double valve in an uppermost position, as shown

in the drawing—that is, with the valve C⁴ seated on the seat C' and the valve C³ off the seat C', so that the steam passes through the 55 casing C into the condenser-casing A.

The lower or inner end of the valve-stem C⁵ reaches into the condenser-casing A and is provided with a collar C⁷, adapted to be engaged by an arm E, held vertically adjustable on the stem F by means of a set-screw E'. The stem F is secured at its lower end to a float G, adapted to rise and fall with the water accumulating in the lower end of the casing A, and the upper end of the said stem 60 F is connected with the spraying-nozzle H, fitted to slide in a pipe H', connected at its outer end with the water-supply pipe I, delivering water to the said nozzle H, so that the water passes in jets into the casing A to 65 condense the steam as the latter passes into the upper end of the casing. On the nozzle H is formed a valve H², adapted to be seated on the inner end of the pipe H', so as to cut off the water-supply to the casing A. Normally the nozzle H is in a lowermost position, 70 as shown in the drawing, so that water can pass from the pipe I, through the spraying-nozzle H, into the casing A; but in case the water is not drawn fast enough from the latter by the pump and this water accumulates 75 in the casing the float G then rises and moves the valve H² upon its seat on the lower end of the pipe H', so as to shut off the supply of the cooling-water. When the pump finally 80 reduces the amount of water in the casing A, the float G moves downward to again open the nozzle H, so as to admit water to the casing from the pipe I. In case the water-supply fails or the water is drawn from the casing A quicker than supplied, the float G sinks, 85 so as to finally engage the arm E with the collar C⁷ to draw the valve-stem C⁵ downward to bring the valve C³ on its valve-seat C', so as to shut the exhaust-steam off from 90 the casing A. At the same time the valve C⁴ is moved off its seat to permit the exhaust-steam passing into the casing C to pass through the valve-seat C² out to the atmosphere. 95

It will be seen that by the float G rising and falling with the water in the casing A more or less water is admitted to the casing by the nozzle H, as some of the perforations 100

of the latter are cut off on the rising of the float G to reduce the amount of water passing into the easing from the pipe I.

The under side of the float G is provided 5 with an upwardly-extending chamber G', into which extends the upper end of the suction-pipe B, so that air-bubbles passing into the easing A are readily drawn through the water into the said chamber and to the suction-pipe 10 B. A spider G² is attached to the bottom of the float G to form a guide for the float on the fixed suction-pipe B.

Having thus fully described my invention, I claim as new and desire to secure by Letters 15 Patent—

1. A condenser for steam-engines, provided with a casing, a float rising and falling with the water in the said casing, and a double valve adapted to be actuated by the said 20 float, to shut the exhaust-steam off from the condenser-casing and to permit the exhaust-steam to pass to the atmosphere, substantially as shown and described.

2. In a condenser for steam-engines, the 25 combination with the condensing-casing, of a valve-casing connected with the condensing-casing and with which the exhaust-steam pipe is connected, two valves in said casing, one for controlling the admission of exhaust- 30 steam to the condensing-casing and the other for allowing the exhaust-steam to escape to the atmosphere, and a float in the condensing-casing and connected with said valves, substantially as described.

3. A condenser for steam-engines, comprising a casing, a float adapted to rise and fall with the water in the said casing, and a spraying-nozzle formed with a valve and fitted to slide in a pipe attached to the casing, the said 35

pipe being formed at its lower end with a 40 valve-seat, and arranged for connection with the water-supply pipe, substantially as shown and described.

4. A condenser for steam-engines, comprising a condenser-casing, a valve-casing connected with the said condenser-casing and connected with the exhaust-steam pipe, the said valve-casing being provided with two valve-seats, a spring-pressed valve-stem carrying two valves for the said seats, an arm 45 adapted to engage a collar on the said valve-stem, and a float adapted to rise and fall with the water in the said casing and provided with a stem carrying the said arm, substantially as shown and described. 55

5. In a condenser for steam-engines, the combination with the condensing-casing, of a valve for controlling the admission of water to the said casing, and a valve for controlling the admission of exhaust-steam into said casing, and a float in the casing and connected with said valves, substantially as described. 60

6. In a condenser for steam-engines, the combination with a condensing-casing, and a water-pipe entering the same, of a spraying-nozzle sliding in the water-pipe and formed with a valve at its lower end, a valve-casing having two valve-seats, one opening into the condenser-casing and the other into the atmosphere, two valves in said casing, and a 65 float in the condenser-casing and connected with the said valves, substantially as herein shown and described. 70
